(57) **CLAIM**

The ornamental design for a cassette for a cutting tool, as shown and described.

DESCRIPTION

FIG. 1 is a perspective top view of a first embodiment of a cassette for a cutting tool;

FIG. 2 is a perspective bottom view thereof;

FIG. 3 is a bottom plan view thereof;

FIG. 4 is a front elevational view thereof;

FIG. 5 is a rear elevational view thereof;

FIG. 6 is a top plan view thereof;

FIG. 7 is a left side elevational view thereof;

FIG. 8 is a right side elevational view thereof.

FIG. 9 is a perspective top view of a second embodiment of a cassette for a cutting tool;

FIG. 10 is a perspective bottom view thereof;

FIG. 11 is a bottom plan view thereof;

FIG. 12 is a front elevational view thereof;

FIG. 13 is a rear elevational view thereof;

FIG. 14 is a top plan view thereof;

FIG. 15 is a left side elevational view thereof;

FIG. 16 is a right side elevational view thereof.

FIG. 17 is a perspective top view of a third embodiment of a cassette for a cutting tool;

FIG. 18 is a perspective bottom view thereof;

FIG. 19 is a bottom plan view thereof;

FIG. 20 is a front elevational view thereof;

FIG. 21 is a rear elevational view thereof;

FIG. 22 is a top plan view thereof;

FIG. 23 is a left side elevational view thereof; and

FIG. 24 is a right side elevational view thereof.
